UNITED STATES PATENT OFFICE.

FERDINAND M. KAUFMAN, OF ATLANTA, GEORGIA, ASSIGNOR TO EMPIRE PRINTING AND BOX COMPANY, OF ATLANTA, GEORGIA, A CORPORATION OF GEORGIA.

BOX.

Application filed March 6, 1923. Serial No. 623,149.

To all whom it may concern:

Be it known that I, FERDINAND M. KAUFMAN, a citizen of the United States, residing at Atlanta, in the county of Fulton and State 5 of Georgia, have invented certain new and useful Improvements in Boxes, of which the following is a specification.

The invention relates to boxes, and has as an object the provision of a box which 10 will be cheap to manufacture and which is provided with a handle in such a manner as to make the box convenient to carry and wherein the handle may be readily folded so as not to project beyond the general 15 contour of the box. A further object of the invention is the provision of a box which is useful for delivery, shipping, or carrying purposes.

Illustrative embodiments of the invention 20 are shown in the accompanying drawings, in which—

Figure 1 is a perspective view;

Figure 2 is a horizontal cross section of the box of Figure 1;

Figure 3 is a plan view of a blank from the side which is inside the box when folded;

Figure 4 is a horizontal cross section showing a modified form of joint.

As shown in Figures 1 to 3 inclusive, the 25 box comprises vertical sides 10, 11, 12 and 13, a bottom 14, and cover flaps 15 and 16.

Handles are conveniently provided, as shown, by flaps 17, 18, extending upwardly from the sides 10 and 11, said flaps being 30 equal in length to the flaps 15, 16 and provided with apertures 19, 20 for reception of the fingers and the thumb, respectively, of the user. If desired, of course, the fingers may be run through both apertures while 35 handling the box. The bottom of the box is shown as formed from tabs 21, 22, 23, 24 of equal length which, when the box is "made up" are folded inwardly and may be secured by means of a binding strip 25 pasted upon the exterior.

A conveniently strong and cheap method of fastening the vertical sides of the box together is shown in Figs. 1 and 2, comprising a tab 26 folded within the side 13 and secured thereto as by means of clinching staples 27.

The length of the flaps 15 and 16 determines one transverse dimension, in this instance the narrower transverse dimension, of the box as will be apparent from a consideration of Figure 1 and the length of the flaps 17 and 18 is equal to the said transverse dimension as Figure 2 best illustrates. As a result, the flaps 17 and 18 may be folded in superposed relation on the flaps 15 and 16 55 or top of the box without projection beyond the sides of the box, which gives extreme compactness to facilitate packing or storing.

In the form of box shown in Fig. 4, the 60 sides 10' and 13' are merely caused to meet at the corner and a strip 28 is folded thereabout and pasted to the two sides.

The box is preferably made of a light but strong material, such as corrugated board, 65 or in fact of any kind of paper board provided with smooth surfaces, and is very desirable for carrying breakables such as eggs or bottles.

It will be seen that the handles or flaps 70 17, 18 when held in one hand by the carrier, perform the double function of supporting the box and contents and also of holding the flaps 15, 16 in closed position. The length of the tabs 21, 22, 23 and 24 being equal and 75 that of 15, 16, 17 and 18 also being equal to each other, the blank from which the box is formed is substantially a rectangle whereby little material is wasted, none in the form 80 of Fig. 4.

I claim:

A box formed from a blank substantially rectangular in outline and comprising a central portion having bottom-forming tabs 85 projecting from one side thereof, and flaps projecting from the opposite side thereof, said flaps being of a length substantially equal to the corresponding transverse dimension of the box, one pair of the flaps 90 overlapping when the box is closed, and completely closing the upper end of the box, the remaining pair of flaps having hand admitting apertures, whereby the box may be carried by a hand of a carrier and said first named flaps held in closed position.

FERDINAND M. KAUFMAN.
